UNITED STATES PATENT OFFICE.

BURT S. HARRISON, OF CHICAGO, ILLINOIS, ASSIGNOR TO DRYING SYSTEMS, INC., OF CHICAGO, ILLINOIS, A CORPORATION OF ILLINOIS.

AIR WASHER.

Application filed February 4, 1922. Serial No. 534,272.

To all whom it may concern:

Be it known that I, BURT S. HARRISON, a citizen of the United States of America, and a resident of Chicago, county of Cook, 5 and State of Illinois, have invented a new and useful Improvement in Air Washers, of which the following is a specification.

This invention relates to a method and apparatus for washing air, not by mechanically operated sprays, but through the result of developing pressure in the air and dividing it into thin sheet-like columns, and causing these moving sheets of air to engage the surface of the water and extend 15 the surface to a very large area compared with the space available in the apparatus, this extension of the water surface being due to the pressure and flow of the air as controlled by the particular construction of 20 the apparatus.

The objects of the invention are to avoid the necessity of using spray heads or other mechanical means for agitating or spraying the water, other than the particular 25 means for developing the desired pressure in the air; to reduce the expense of construction of air washing machines; and to vastly increase the efficiency of static washers by arranging for a large surface contact be- 30 tween the moving air columns and water. A further object of the invention is to arrange for centrifugal motion of foreign par- 35 ticles through the air and into contact with the water surface. It is also an object of the invention to overcome the objectionable throwing out of the washer of most of the 40 water or causing too much entrained water to travel with the air as occurs in other forms of static air washers.

45 The objects of the invention are accom- plished by the construction shown in the accompanying drawing, wherein—

Figure 1 is a diagrammatic view in side elevation of an air washer constructed ac- 45 cording to this invention.

Fig. 2 is a sectional view taken on the line 2—2 of Fig. 1.

Fig. 3 is a diagram illustrating the action of the air columns on water within a par-

titioned tank at the bottom of the apparatus.

In its general feature the air washing apparatus shown in the drawing comprises a plurality of narrow and considerably elongated entering ducts or passages for the air. 55 These passages lead downwardly to the surface of the water in a tank and are about one-half inch wide. The partitions which form both the alternating inlet and outlet passages terminate at the lower edges, 60 extending along the water level. The water level in the washer will drop under each air inlet proportionate to the static pressure. When the static pressure of one-quarter inch water column on the air has 65 been reached, the water surface is forced down from its normal level one-quarter inch water column by the force of the currents of air passing from the inlets to the outlets around the lower edge of the partitions. 70 The water surface takes a semi-circular or concave form below the inlets and outlets and extends upwardly along the walls of the outlets until caught by inverted gutters inclined from the center to both ends, where 75 the water which has been caught is drained back into the pan. The furrows on the surface of the water, caused by the air pressure and its flow, are multiplied by the use of a number of partitions just below the 80 normal surface of the water, one being placed between each of the partitions forming air inlets and outlets. The air currents being very shallow (one-quarter inch) in turning the sharp elbow of one-quarter 85 inch radius of the furrowed water surface, due to centrifugal force throw dust or other foreign particles carried by the air into contact with the water surface.

Because of the narrow air currents and 90 the small water depressions necessary to let the air pass, it is possible to operate by fan suction as well as by fan pressure without blowing the water out of the pan. The water is held at the desired level by means 95 of a float valve in an adjoining chamber on the side of the washer.

Referring to the drawings, the casing 1

of the apparatus is suitably formed to provide a large air inlet duct 2, and an air outlet duct 3, and a water-containing pan or tank 4. The tank portion of the apparatus 5 is divided by the partition 5 into a float chamber 6 at one side of a chamber 7 which contains the water acted upon by the moving sheet-like columns of air. The level of the water is controlled by a float valve 8 in chamber 6. The water inlet is indicated at 9, the outlet for waste at 10, and an overflow at 11. The normal water level is indicated by the dotted line 12, but when the apparatus is in operation the surface 13 of the water assumes the shape indicated by the dotted line 13, Figure 3. The main body 14 of the apparatus is divided by a plurality of vertical partitions 15 extending from the upper surface of casing 1 20 downwardly in more or less triangular form as indicated in Figure 1, to the normal surface 12 of the water. The upper edges 16 of the partitions, in order to provide a set of air inlet conduits 17 alternating 25 with a set of air outlet conduits 18, are alternately connected together on opposite sides of the apparatus by the closing strips 19. Thus the air enters by a plurality of spaced conduits and leaves through 30 the space between these conduits. Centrally located below each air supply conduit 17 is a vertical partition 20 extending from end to end of the air supply conduits, but having its upper edge terminate at the normal 35 water level 12 and in line with the lower edges 21 of the partitions 15. These partitions serve to cause the water surface to assume the furrows of approximately one-quarter inch radius when the surface is 40 pressed downwardly by the air flowing around the lower edges 21 of the partitions 15.

Vertically extending eliminator plates 22 are centrally located in the lower part of 45 the outlets 18. These eliminator plates are provided with inverted gutters 23 at their upper edges in order to guide the water flowing up the surfaces of the eliminator plates towards the ends of the apparatus and back 50 into the tank. For this purpose the gutters 23 are inclined downwardly from the center of the apparatus to its ends. The inverted gutters of course also prevent water from flowing upwardly and out of the outlet 55 let 3 with the air.

In the operation of the device, the air is delivered to conduit 2 by fan pressure, or may be caused to pass through the apparatus by the suction of a fan to the outlet conduit 3. As soon as sufficient static pressure is developed in the inlet conduits 17, or suction in the outlets, the water surface is depressed into the furrowed form as indicated by the dotted lines 13, thus 65 bringing about a very extended water sur-

face with which the air intimately contacts due to its sheet-like form. The centrifugal action developed by the velocity of the air in rounding the beaded lower edges 21 of partitions 15 results in positively throwing 70 dirt particles entrained in the air against the surface of the water and thereby thoroughly cleansing the air of the heavier particles, whereas the surface contact alone is relied upon for taking up the lighter dust 75 particles or dust.

The type of washer above described has the advantage that no power is required for moving parts such as spray pumps or revolving drums. The design is flexible in 80 that it can be made up of a standard size or shape of narrow air passages and the capacity varied by the number of sections used, and, of course, this washer requires less total space than the usual spray washers even when having far less capacity.

Although but one specific embodiment of this invention has been herein shown and described it will be understood that numerous details of the construction shown 90 may be altered or omitted without departing from the spirit of this invention as defined by the following claims.

I claim:

1. An apparatus of the class described 95 constructed to include a plurality of alternating narrow parallel air inlet and outlet passages, communication being provided between these passages at their lower ends due to the pressure of the air upon the water 100 surface at said lower edges, vertical partitions extending along the lower ends of the air inlet passages and downwardly to below the normal water level.

2. An apparatus of the class described 105 constructed to include a plurality of alternating narrow parallel air inlet and outlet passages, communication being provided between these passages at their lower ends due to the pressure of the air upon the water 110 surface at said lower edges, eliminator plates equipped with inverted gutters extending along said outlet passages.

3. An apparatus of the class described 115 constructed to include a plurality of alternating narrow parallel air inlet and outlet passages, communication being provided between these passages at their lower ends due to the pressure of the air upon the water surface at said lower edges, vertical partitions extending along the lower ends of the air inlet passages and downwardly to below the normal water level, and eliminator plates equipped with inverted gutters extending along said outlet passages.

4. An apparatus of the class described, 120 comprising a casing, means for maintaining a normal water level therein, a plurality of substantially parallel walls extending between said water level and the top of the 130

casing and subdividing same into alternate inlet and outlet passages, a partition extending along the bottom of each of said air inlet passages midway between the walls thereof and from the water level to a substantial distance below the water level, a partition extending along the bottom of each of said outlet passages midway between the walls thereof and both above and below the water level, and means for trapping the flow of water upward along and beyond said last named partitions.

Signed at Chicago this 30th day of January 1922.

BURT S. HARRISON.
